UNITED STATES PATENT OFFICE.

WILLIAM K. HENRY, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

DOOR-CONTROLLING MEANS.

1,079,763.

Specification of Letters Patent.

Patented Nov. 25, 1913.

Application filed July 9, 1913. Serial No. 778,038.

To all whom it may concern:

Be it known that I, WILLIAM K. HENRY, a citizen of the United States, residing at New Britain, Hartford county, State of Connecticut, have invented certain new and useful Improvements in Door-Controlling Means, of which the following is a full, clear, and exact description.

My invention relates to an improved door closer and check of the so-called sill type, and the object of the invention is to provide various improved features of construction aiming at simplicity and ease of adjustment, durability and effectiveness of operation.

In the drawings: Figure 1 is a plan view with the top plate or cover removed. Fig. 2 is a side elevation, partly in section. Fig. 3 is a central longitudinal section. Fig. 4 is a cross section. Figs. 5, 6, 7, 8 and 9 illustrate details of construction.

1 represents the main casing or frame which provides two spaced chambers separated by a partition 2. The upper chamber contains the closer mechanism, while the lower chamber (cylindrical in form) contains the checking mechanism.

3 is a spindle suitably mounted in the main casing 1, the lower part of said spindle having a segmental gear 3^a for operating a piston 4, said piston having two opposite sets of rack teeth 4^a on each side of a slot therein for engagement by said gear segment, so that when the spindle is turned in either direction, it will operate the piston. The piston is provided with a head 4^b which properly fits in the cylindrical checking chamber, which latter contains liquid whereby the movement of the piston is retarded when moving in one direction. A check valve 5 in the piston head 4^b, or other suitable mechanism, permits the piston to move freely in an opposite direction. The cylindrical checking chamber is provided with a by-pass for the liquid, which by-pass may be formed in an extension 6.

7 is a valve controlling the by-pass.

6^a is a by-pass groove in the inner side wall of the cylinder leading from the end of the offset by-pass to the capped end of the cylinder.

8 represents a removable cap at the end of

the checking cylinder for gaining access to the interior.

9 represents a suitable bearing and stuffing box for the spindle 3.

10 represents a lever arm mounted on the upper end of the spindle outside of the casing.

1^a represents the top plate or cover for the casing 1. The cover 1^a has what may be termed a hand hole therein provided with a closure plate 1^b which may be detached at any time to afford access to the interior closer mechanism. The spindle 3 has fixed thereto an eccentric preferably in the form of a double crank extension 11 carrying the pins 12—12^a at each end.

14 is a slide mounted to slide longitudinally in the guide-way in the upper chamber of the casing 1.

15 is an adjustable cross-head carried by the slide 14 and adjustable longitudinally relatively thereto. The preferable means of adjustment comprises a threaded stem 16 carried by the cross-head upon which is mounted a nut 17 bearing against an abutment or shoulder on the slide 14 (as shown in Fig. 1). By turning the nut 17, the cross-head can be moved to and fro.

18 is an adjustable hook carrier pivotally mounted at 20 on the slide 14, preferably underneath the same, said carrier pivotally carrying the links or hooks 19 and 19^a, the ends of which respectively engage the studs or pins 12, 12^a of the double crank 11. The carrier 18 may be angularly adjusted on its pivot 20 to vary the effective positions of the hooks 19—19^a. Suitable means is provided to lock the hook carrier 18 when properly adjusted. The preferred means comprises one or two clamping screws 21—21, which pass through slots in the slide 14 and into threaded openings in the carrier 18 as shown, so that by loosening up on said screws, the frame may be shifted. 22—22 are spiral compression springs both of which at one end press against the end wall of the casing 1, and both of which at the other end press against the cross-head 15. The upper chamber within the frame or housing 1 is preferably provided with parallel side channels to receive, guide or steady the springs 22. By

reason of the fact that the maximum length of spring is employed (practically the full length of the case), a very substantial factor of safety and durability largely in excess of 5 the limit required, is guaranteed.

In operation, the check should first be fitted to the particular door with which it is to be employed. If for any reason the arm or lever 10 does not correctly aline with 10 the door casing or sill, it requires but a moment to loosen the clamping screws 21 and to shift the position of the hook carrier 18 so that the proper alinement of the lever 10 can be effected. When this is effected, 15 the clamping screws 21 are set down tightly. If more or less pressure is desired, this may be varied by shifting the tension adjusting nut 17. As soon as the correct adjustment has been established, the hand hole cover 1^b 20 may be restored in place and the entire mechanism is then ready for service as soon as the door proper has been secured to the lever 10.

While the pivots for the hooks 19 and 19^a 25 on the carrier 18 are on each side of the center line of the closer, they are nevertheless preferably close thereto and at a less distance therefrom than the clamping screws 21 so that it takes a longer movement of the 30 ends of the carrier to shift the relative position of the hooks 19 and 19^a than would be the case if these pivot points for the hooks were farther away from the center. By this 35 construction a very slight strain on the clamping screws 21 serves to effectively hold the carrier, when adjusted, against accidental displacement. As shown in Fig. 1, access may be readily had to the by-pass valve 7 when the cover 1^a is removed, an 40 opening in the flange of the case 1 being provided directly above the stem of the valve 7 to permit a small key or wrench to be inserted. It will be observed that by reason of the unique construction herein described, the various parts may be assembled 45 in very compact arrangement and yet easy access may be had at any time for the purpose of adjustment or repair. By providing two spiral compression springs, there is 50 a balanced pressure on the cross-head, tending to prevent the binding of the slide in its guide-way as it reciprocates. These and many other advantages, unnecessary to particularly point out, resulting from the novel 55 construction herein disclosed, will be apparent to the mechanic skilled in this art.

What I claim is:

1. In a door closer mechanism, a casing, a door-controlling spindle rotatably mounted 60 therein, a slide arranged to reciprocate in said casing, an eccentric on the spindle, a connection between said eccentric and said slide, a pair of spiral compression springs arranged on opposite sides of the spindle 65 and operatively connected with said slide,

and means for adjusting the operative connection between said springs and said slide said springs extending substantially the full interior length of the casing.

2. In a door closer mechanism, a casing, a 70 door-controlling spindle rotatably mounted therein, a slide arranged to reciprocate in said casing, an eccentric on the spindle, a connection between said eccentric and said slide, a pair of spiral compression springs 75 arranged on opposite sides of the spindle and operatively connected with said slide, and means for adjusting the operative connection between said springs and said slide, said means including a movable cross-head 80 carried by said slide.

3. In a door closing mechanism, a casing, a door controlling spindle rotatably mounted therein, a slide arranged to reciprocate in said casing, an eccentric on the spindle, a connection between, said eccentric and said slide, a pair of spiral compression springs arranged on opposite sides of the spindle and operatively connected with said slide, 85 said casing having a pair of channels 90 formed therein in which said pair of spiral springs is located, the opposite side walls of each of said channels affording a support for the opposite sides of each spring to prevent buckling.

4. In a door closer mechanism, a casing, a door-controlling spindle rotatably mounted therein, a slide arranged to reciprocate in said casing, an eccentric on the spindle, a connection between said eccentric and said slide, a pair of spiral compression springs 100 arranged on opposite sides of the spindle and operatively connected with said slide, means for adjusting the operative connection between said springs and said slide, 105 said casing including a removable cover plate, said cover plate having a hand-hole passage therein to afford access to the adjusting mechanism, and a removable cover for said hand hole.

5. In a door closer mechanism, a casing, a door-controlling spindle rotatably mounted therein, a slide arranged to reciprocate in said casing, a double eccentric on said spindle, means for connecting said slide with 110 said eccentrics including a pair of hooked links, a pair of spiral compression springs arranged on opposite sides of the spindle and operatively connected with the slide.

6. In a door closer mechanism, a casing, a door-controlling spindle rotatably mounted therein, a slide arranged to reciprocate in said casing, a double eccentric on said spindle, means for connecting said slide with said eccentrics including a pair of links, with means for adjusting the normal position of said links, and a pair of spiral compression springs arranged on opposite sides of the spindle and operatively connected with the slide.

7. In a door closer mechanism, a casing, a door-controlling spindle rotatably mounted therein, a slide arranged to reciprocate in said casing, a double eccentric on said spindle, means for connecting said slide with said eccentrics including a pair of links, with means for adjusting the normal position of said links, said means comprising a carrier pivoted to the slide, with means for adjusting the angular position of said carrier, and a pair of spiral compression springs arranged on opposite sides of the spindle and operatively connected with the slide. 30
- 10 8. In a door closer mechanism, a casing, a door-controlling spindle rotatably mounted therein, a slide arranged to reciprocate in said casing, a double eccentric on said spindle, means for connecting said slide with said eccentrics including a pair of links, with means for adjusting the normal position of said links, said means comprising a carrier pivoted to the slide, with means for adjusting the angular position of said carrier, said links being pivoted to the car- 35
- 20 9. In a door closer mechanism, a casing, a door-controlling spindle rotatably mounted therein, a slide arranged to reciprocate in said casing, a double eccentric on said spindle, a connection between each end of said eccentric and said slide including two separate links each having a relatively sliding connection with said eccentric, with means for adjusting the position of said links, a pair of spiral compression springs arranged 40 on opposite sides of said spindle and adjustably and operatively connected with said slide, in combination with a door checking mechanism operatively connected with said spindle, and including a checking cylinder 45 and checking piston therein.
